UNITED STATES PATENT OFFICE.

PERLEY R. GLASS, OF WAYLAND, MASSACHUSETTS, ASSIGNOR TO UNITED SHOE MACHINE CORPORATION, OF PATERSON, NEW JERSEY, A CORPORATION OF NEW JERSEY.

MARKING MACHINE.

Application filed March 20, 1925. Serial No. 17,121.

This invention relates to marking machines and more particularly to marking machines designed to print a row of characters and arranged so that the markers may be 5 rapidly interchanged between printing operations.

The use of marking machines is common in factories for manufacturing boots and shoes and in many other places for imprinting a row of characters upon a plurality of 10 pieces of material or articles and when a marking machine is employed for such a purpose it is essential, for satisfactory use of the machine, that the operator shall be 15 able quickly and accurately to interchange the markers upon the marking head without danger of soiling the hands or, in case the printing characters are heated, of burning the fingers. An object of the present invention is to provide a marking machine having 20 an improved mechanism for setting the printing elements which will be arranged so that the operator may make the desired changes rapidly and accurately without encountering any of the difficulties above mentioned.

With this object in view, a feature of the invention relates to a novel setting device which may be brought into engagement with 30 any one of a plurality of adjustable markers. As illustrated, the markers are disks and displaceable retaining latches are provided for each of the disks and the setting device is so interconnected with the retaining latches 35 that a latch which has been displaced to release one of the disks acts as a stop for the setting mechanism to indicate to the operator that the setting device is in co-operative relation with the particular disk which has 40 been released. The illustrated setting device is mounted for movement within the hubs of the various disks and is provided with a rod mounted for movement outside the disks in a path which intersects any latch which 45 has been displaced.

These and other features of the invention as pointed out in the appended claims will be best understood from a consideration of the following specification taken in connection with the accompanying drawings, in 50 which—

Fig. 1 is a side elevation of the machine with parts broken away;

Fig. 2 is a fragmentary view showing the marking head in printing position; 55

Fig. 3 is a front elevation of the machine with parts broken away;

Fig. 4 is a perspective view of the marking head and the setting mechanism; and

Fig. 5 is a vertical section through the 60 marking head and the setting device.

The frame 10 of the machine comprises end members 12 and 14 between which a power shaft 16 and a crank shaft 18 are supported. Power may be supplied to the machine in any desired manner but as herein illustrated it will be used to rotate a belt pulley 20 loosely mounted upon the shaft 16 and adapted to be clutched to said shaft by a friction disk 22. A pinion 24 (Fig. 3) upon 70 the power shaft 16 meshes with a gear 26 on the crank shaft 18 and supplies power to rotate the latter when the clutch is closed. It is desired that the clutch shall be so arranged that the crank shaft 18 will make one 75 or more complete revolutions and then stop, and to this end a cam 30 is mounted upon the crank shaft 18 which acts against a lever 32 pivotally mounted upon a transverse rod 33 and held against the cam by a spring 80 35 to move a bifurcated lever 34 also mounted on said rod and, at the desired time, pull the clutch disk 22 out of engagement with the driving pulley 20 against a tension spring 36 mounted upon the power shaft 16. The connection between the levers 32 and 34 is not a fixed connection, however, and it 85 comprises a latch 38 pivoted upon the lever 32 and resiliently held against a stop screw 40 by a spring 41. This latch 38 engages the 90 notch of a horizontal rod 42 pivotally connected at one end to the bifurcated lever 34 and at the other end to a treadle rod 44. This places the mechanism in such condition that an upward movement of the treadle rod 44 under the control of the operative releases 95 the horizontal rod 42 and allows the spring 36 to throw the clutch into operative engagement with the driving pulley 20, thereby 100 supplying power to the crank shaft 18 and effecting rotation of the latter. As soon as the treadle rod 44 is released by the operator the latch 38 will again slip into position for engagement with the notch in the horizontal rod 42 so that the cam 30, acting through the 105 lever 32 and the now connected lever 34, will

become effective to throw out the clutch at the completion of a full revolution of the crank shaft 18.

The marking head is supported in a hanger 50 which is pivotally mounted upon the outer end of parallel links 52 and 54 which are pivoted within the frame of the machine, so that the hanger 50 is maintained in substantially vertical position as it is moved up and down to bring the printing characters into and out of engagement with the work. The link 54 is extended to the rear, as shown in Fig. 1, where it is connected by means of a link 56 with a crank 58 on the crank shaft 18.

The marking head comprises adjustable markers for printing characters, which will be described more in detail, and ink is supplied to said markers by means of an inking device comprising a rotatable cylinder 60 mounted upon the frame of the machine and adapted to be kept coated with ink from a reservoir 62 placed over the rear upper quadrant of the supply cylinder 60 in a position where it may conveniently be filled as desired and, by virtue of a scraper plate 64 adjustable by means of a screw 66, may be caused to supply a film of marking material to the rotatable cylinder 60. To transfer the ink from this cylinder to the markers a transferring roll 70 is carried upon the outer end of an arm 72 pivoted at its upper end in the frame of the machine and actuated by means of a link 74 which is connected to an extension 76 upon the upper parallel link 52 so that it is brought into position to wipe across the markers as the marking head moves into inoperative position and to wipe across the supply cylinder 60 as the marking head moves into printing position, as shown in Fig. 2. It will be noted that the transferring roll is carried upon a pivoted extension 78 of the arm 72 which is spring pressed upwardly by a spring 80 to hold it resiliently in engagement with either the markers or the supply roll as the transferring roll 70 is caused to wipe across first one and then the other.

It is frequently desired to use a machine of this type for marking a stack of similar pieces of work, as indicated in Figs. 2 and 4, and to facilitate the use of the machine for such an operation a work table 82 is provided having a post 84 slidably mounted in a suitable bearing 86 formed at the outer end of a bracket 88 on the frame of the machine. Interposed between this bearing and the work table is a spring 90 the tension of which may be adjusted by means of a screw 92 and the range of movement of the table with respect to the bearing sleeve is limited by the engagement of a stop screw 94 in the sleeve with a slot 96 in the post 84. A holding latch 98 is then provided which has a locking cam positioned for engagement

with the side of the post 84 to hold it in adjusted position when said latch 98 is pressed downwardly and to release the table for upward movement under the tension of the spring 90 when the latch 98 is moved to upward position. Mechanism is then provided for automatically controlling the latch 98 so that the table is released for automatic positioning by means of the combined action of the marking head on the stack of work and the tension of the spring 90 with the result that the pressure of the marking head upon the work is kept uniform regardless of the number of pieces of work underneath the marking head. This allows the operator to hold the work in the manner indicated in Fig. 2 and to allow one piece after another to drop into position for engagement by the marking head without fear of producing an excessive pressure of the marking head when a stack of pieces has accumulated. The automatic mechanism controlling the latch 98 includes a rod 100 pivotally mounted at 102 upon an extension 104 of the parallel link 54 and slidably engaged at 106 with the outer end of the controlling latch 98. A head 108 is provided upon the rod 100 to lift the latch to release the post 84 of the table when the rod 100 has moved to upward position accompanying a downward movement of the marking head. When the marking head has moved to inoperative position, however, the rod 100 is moved to the position indicated in Fig. 1 and thereby tensions a spring 110 surrounding said rod and interposed between the controlling latch 98 and a stop 112 on the rod. This causes the controlling latch 98 to bite against the post 84 of the table and hold it against the tension of the spring 90.

The arrangement of the marking head is best shown in Figs. 3, 4 and 5 from which it will be seen that the lower end of the hanger 50 is bifurcated to provide vertical arms 114 and 116 and a hollow supporting member 118 is mounted upon the arm 116 by screws entering a flange 120 in said hollow support. Surrounding this hollow support and rotatable with respect to it is a slotted sleeve 122 having oppositely positioned slots of which parts are filled by the rods 124 and 126 of the setting device. A plurality of adjustable markers are provided in the form of disks 130 rotatably mounted upon the slotted sleeve 122 and in the illustrated embodiment these disks are provided with teeth upon their external peripheries carrying printing type-faces. It should be noted that the setting device to be described is not limited in use to an arrangement in which the type-faces are placed directly upon the disks with which the setting device is associated but may also be used with an arrangement (not shown) having a plurality of series of disks inter-

engaged with one another so that the type-faces are carried upon one of the series which is remote from the particular series adjusted by the setting device. These disks 5 130 are notched upon their inner peripheries as indicated in Fig. 5 so that there is a notch corresponding to each of the teeth upon the outer periphery. When the disks are held in printing position (by which is meant an 10 alined position ready to print) the notches of the various disks will be alined to form the grooves which appear in Fig. 5. This arrangement enables the rod 126 of the setting device to be provided with a tooth 132 15 engaging the notches upon the inner peripheries of the disks and is slidably transversely of said disks to bring it into co-operative relation with any particular disk of which it is desired to change the position. Preferably, the position of the various disks upon 20 the support is determined by means of displaceable pivoted retaining latches 134 which may be of any convenient construction and preferably are arranged substantially as shown in U. S. Letters Patent No. 25 984,588, granted February 21, 1911 on the application of F. W. Merrick. If desired for the particular use to which the machine is put, a size lever 136 (Fig. 3) may be provided 30 which is arranged according to the principle described in said patent so that its operation causes the size wheels to be changed step by step to indicate a series of sizes and half sizes. The rods 124 and 126 35 are mounted upon a head 140 (Fig. 5) to which there is connected a setting wheel 142 and a bracket 144 is pivotally mounted upon this head and held rigidly against movement along the axis of the disks. This 40 bracket 144 carries a rod 146 passing through a bearing 148 (Fig. 4) in the arm 114 and moving in a path intersecting the position of the retaining latches 134 when any one of them has been displaced to release the 45 corresponding disk. It should be noted from Fig. 5 that the length of the rod 146 is such that it will engage the side of the retaining latch corresponding to the particular disk with which the tooth 132 of the 50 setting rod 126 is positioned in engagement.

When the operator desires to adjust the markers upon the marking head, he will depress a particular latch 134 corresponding to the disk whose position it is desired to 55 change. The setting device may then be moved laterally until the rod 146 contacts with the particular latch which has been displaced. This positioning movement of the setting device will bring the tooth 132 upon the rod 126 in engagement with the notch on 60 the inner periphery of the particular disk which has been released by the displacement of one of the latches 134. This disk may then be rotated by turning the wheel 142 65 after which the operator will allow the latch

134 to fall into locking position under tension of a spring, not shown, and the machine will be ready for operation or for the setting of another disk if this becomes necessary. If it is desired to heat the disks of the 70 marking head an electric cartridge unit 150 may be inserted within the hollow support 118 thereby to supply heat to said disks. The arrangement illustrated includes a type carrying plate 152 (Fig. 1) carried in alinement with that row of printing type-faces which is in set position and this plate is retained in position by means of a latch 154. 75

When the operator depresses the treadle connected to the rod 44 to raise said rod the 80 clutch will be thrown into engagement and the machine caused to bring the marking head against one after another of the pieces of work as the operator drops them under said head in the manner indicated in Fig. 2. 85 The machine will always stop in the same position at the completion of a full revolution of the crank shaft 18 after the operator releases the treadle rod 44 to allow it to drop, whether the machine has completed 90 only one or any number of printing operations.

Having described my invention, what I claim as new and desire to secure by Letters Patent of the United States is:

1. In a marking machine, a support, a plurality of adjustable markers mounted side by side upon said support, a setting device movable laterally to bring it into co-operative relation with one of said markers, and 100 co-operating operator-controlled mechanisms for stopping the lateral movement of the setting device when it has reached the particular marker which the operator desires to set.

2. In a marking machine, a plurality of adjustable markers mounted in parallel planes, a setting device movable from one to another of said markers to position it in co-operative relation with the particular marker 110 which it is desired to adjust, and operator-controlled mechanism for stopping the positioning movement of the setting device when it has reached the particular marker which it is desired to adjust.

3. In a marking machine, a support, a plurality of markers adjustably mounted upon said support, displaceable members associated with said markers, and a setting device movable laterally to bring it into co-operative relation with one of said markers, said setting device being constructed and arranged so that when its movement is impeded by the displacement of one of said members it is then in position to adjust a particular marker with which the displaceable member is associated.

4. In a marking machine, a support, a plurality of disks rotatably mounted upon said support, displaceable members associated 130

- with said disks, a setting device movable laterally to bring it into co-operative relation with one of the disks, said setting device being constructed and arranged so that its movement is impeded by the displacement of one of said members and so that it is then in position to set the particular disk with which the displaceable member is associated.
5. In a marking machine, a plurality of markers each of which is provided with type-faces and is adjustable to bring any one of the type-faces into printing position, displaceable members associated with said adjustable markers, a setting device movable laterally to bring it into co-operative relation with one of the markers, and means movable laterally with said setting device in a path such that it will engage whichever one of the displaceable means has been moved out of normal position and will thereby indicate to the user that the setting device is in co-operative relation with the particular marker whose displaceable means has been moved out of normal position.
10. 6. In a marking machine, a plurality of rotatable disks, displacement members associated with said disks, a setting device movable laterally to bring it into co-operative relation with one of the disks, and means movable laterally with said setting device in a path such that it will engage whichever one of the displaceable means has been moved out of normal position and will thereby indicate to the user that the setting device is in co-operative relation with the particular disk whose displaceable means has been moved out of normal position.
15. 7. In a marking machine, a plurality of adjustable markers each of which is provided with a series of type-faces, a setting device co-operating with any one of said markers arranged to bring the desired type-face into printing position, said setting device being movable to position it in cooperative engagement with a desired marker, and displaceable retaining latches for each of said markers, said setting device being so interconnected with the retaining latches that a latch which has been displaced to release one of the markers acts as a stop for the positioning movement of the setting device to indicate that the setting device is in cooperative relation with the particular marker which has been released by the displacement of its retaining latch.
20. 8. In a marking machine, a support, a plurality of disks rotatably mounted upon the support, displaceable retaining latches for said disks, a setting device movable laterally to bring it into co-operative relation with any particular disk, and means movable laterally with said setting device constructed and arranged to contact with one of said latches when it has been moved out of retaining position thereby to indicate that the

setting device is in co-operative relation with the particular disk which has been released by displacement of the retaining latch.

9. In a marking machine, a hollow support, a plurality of disks rotatably mounted upon the support, displaceable retaining latches for said disks, a setting device movable laterally within the hubs of the disks to bring it into co-operative relation with any particular disk, and means movable laterally with said setting device outside said disks in a path so that it will engage a latch which has been displaced to release a disk and thereby indicate to the operator that the setting device is in co-operative relation with the particular disk which has been released.

10. In a marking machine, a support, a plurality of disks rotatably mounted upon the support, a displaceable retaining latch associated with one of said disks, rotatable setting means for said disks slidably mounted within the hubs of the disks and arranged to be brought into engagement with the particular disk which it is desired to turn, a rod movable laterally with said setting means arranged to engage said latch when the latter has been displaced to release the disk, thereby to indicate the co-operation of the setting device with the particular disk which has been released by the displacement of the latch.

11. In a marking machine, a support, a plurality of disks rotatably mounted upon said support and provided with aligned openings, a rotatable setting member movable laterally through said aligned openings and arranged to co-operate with one of said disks to rotate it upon its support, displaceable means associated with one of said disks, and means movable laterally with said setting means arranged to be brought into engagement with said displaceable means in one position of the latter thereby to determine the position of the setting means for co-operation with the particular disk with which the displaceable means is associated.

12. In a marking machine, a support, a plurality of disks rotatably mounted upon said support and provided with aligned openings, a rotatable setting device provided with a lateral projection in the line of said openings to engage the setting device with a particular disk, a rod movable laterally with said setting device, and displaceable means associated with each of said disks adapted to be moved into the path of said rod thereby to indicate that the lateral projection upon the setting device is in engagement with and adapted to turn the particular disk associated with the particular displaceable means which has been moved.

13. In a marking machine, a support, a slotted sleeve rotatably mounted upon said support, a plurality of disks rotatably mounted upon said sleeve, displaceable mem-

bers for holding said disks against rotation, a setting device slidably mounted within the slot of said sleeve adapted to be brought into co-operative relation with any particular disk, and means co-operating with said setting device and said displaceable members in one position of the latter to indicate to the operator that the setting device is in engagement with the particular disk which 10 has been released by the displacement of its retaining member.

14. In a marking machine, a support comprising a hollow member, a sleeve having a longitudinal slot rotatably mounted upon 15 said hollow member, a plurality of disks rotatably mounted on said slotted sleeve, each of said disks having printing types upon its outer periphery and notches on its inner periphery corresponding to the types, and a 20 rotatable setting device having an arm in the slot of said sleeve with a projecting tooth on said arm adapted to enter the notches in said disks.

15. In a marking machine, a support comprising a hollow member, a sleeve having a longitudinal slot rotatably mounted upon 25 said hollow member, a plurality of disks rotatably mounted on said slotted sleeve each of said disks having printing types upon its outer periphery and notches on its inner periphery corresponding to the types, a rotatable setting device having an arm in the slot of said sleeve with a projecting tooth on said arm adapted to enter the notches in 30 said disks, and a heating device within 35 said disks, and a heating device within said hollow support.

16. In a marking machine, a support comprising a hollow member, a slotted sleeve rotatably mounted upon said hollow member, a plurality of disks rotatably mounted 40 on said slotted sleeve each of said disks having printing types upon its outer periphery and notches on its inner periphery corresponding to the types, a rotatable setting device having an arm in the slot of said 45 sleeve, a projecting tooth on said arm adapted to enter the notches in said disks, and operator-controlled means for stopping said setting device when it has reached the particular disk which the operator desires to 50 change.

17. In a marking machine, a support comprising a hollow member, a slotted sleeve rotatably mounted upon said hollow member, a plurality of disks rotatably mounted 55 on said slotted sleeve each of said disks having printing types upon its outer periphery and notches on its inner periphery corresponding to the types, a rotatable setting device having an arm in the slot of said 60 sleeve, a projecting tooth on said arm adapted to enter the notches in said disks, displaceable retaining latches for said disks, and means co-operating with said setting device and said latches to stop the setting 65 device with its tooth in engagement with the notch of any particular disk for which the retaining latch has been moved out of holding position.

In testimony whereof I have signed my 70 name to this specification.

PERLEY R. GLASS.
